[57] CLAIM

The ornamental design for the modular housing for electronic systems, as shown.

DESCRIPTION

FIG. 1 is a top, front, right side perspective view of a modular housing for electronic systems showing my new design;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a bottom plan view thereof.
